HYDRAULIC COUPLING

Willy Black, Berlin-Halensee, and Rudolf Fichtner, Berlin, Germany, assignors to General Electric Company, a corporation of New York

Application May 3, 1939, Serial No. 271,554
In Germany May 11, 1938

4 Claims. (Cl. 60—54)

Our invention relates to hydraulic couplings, and more particularly to the Föttinger type of couplings which are sometimes referred to as hydro-kinetic couplings.

One object of our invention is to provide an improved structure wherein elements of the coupling having different temperature coefficients of expansion may operate in relation to each other throughout the full range of operating temperatures without creating undue strains within the coupling.

For a better understanding of our invention, together with other and further objects thereof, reference is had to the following description taken in connection with the accompanying drawings, and its scope will be pointed out in the appended claims.

In a coupling of the type above-mentioned, the casing is made of cast iron, or of steel, which has a relatively low temperature coefficient of expansion, and the diaphragms within this casing are made of light weight metal such as aluminum, or aluminum alloys, for example, which have a relatively high temperature coefficient of expansion. The temperature range between summer full load operating temperatures and winter starting temperatures is approximately between 100° C. and —20° C. Over this range of 120°, the diameter of a 400 mm. steel casing may vary as much as .53 mm. and the diaphragm of aluminum or an alloy thereof will expand as much as twice that amount. The difference in the expansions of the two metals is, therefore, more than .5 mm., and in the normal range between +20° C. and 100° C., approximately one-third mm. of expansion can be expected. If, therefore, these parts are assembled without sufficient clearance, stresses will be set up within the casing which approach the elastic limit of the metal and, in apparatus where the casings rotate, additional centrifugal stresses will be set up by the mass of the parts and by the mass of the fluid within the coupling.

In accordance with our present invention, the above-mentioned stresses, which are due to unequal temperature coefficients of expansion, are reduced and, in some cases, substantially eliminated.

In the accompanying drawings, Fig. 1 is a cross-sectional elevation of a hydraulic coupling of the Föttinger type in which the guide vane diaphragm is mounted in the casing, with provision being made for radial expansion in accordance with our invention; Fig. 2 is a plan elevation of the diaphragm of Fig. 1; Fig. 3 is

5 a cross-sectional elevation illustrating a modification of the guide diaphragm structure of Figs. 1 and 2; Fig. 4 is a plan view of the diaphragm of Fig. 3; Fig. 5 is another modification of the diaphragm structure illustrated in Fig. 1; Fig. 6 is a modification of Fig. 5 and Fig. 7 is a modification of Fig. 2.

10 Referring to the drawings in detail, Fig. 1 is a cross-sectional elevation through the center of a Föttinger type coupling. This type coupling is described in detail in U. S. Patents 1,199,359 to 1,199,361, issued to Föttinger. As shown in Fig. 1, this coupling comprises a metal casing made up of cast iron or steel shells 11 and 12 joined together along their peripheral flanges 13 and 14. A driving shaft 15 projects through a bearing sleeve 16 in the shell 12 and supports a pump wheel 17. A driven shaft 18 projects through a sleeve 19 in the shell 11 and supports a turbine wheel 20 within the casing. The pump wheel 17 is provided with impeller vanes 21, the outer ends of which are held by a shroud 22. The turbine wheel is provided with vanes 23, the outer ends of which are held by a shroud 24. Fluid in the casing is impelled by the pump vanes 21 against the turbine vanes 23 and is discharged by the latter into a return channel formed by the stationary guide diaphragm with the casing wall. This diaphragm comprises an outer, or shroud, ring 25, an inner, or central, ring 26, and guide vanes 27 connected between these two rings. The inner, or central, ring 26 is shaped to form a channel having the necessary width for conducting the operating fluid within the casing from the discharge side of the turbine vanes to the intake side of the pump vanes, the guide vanes 27 in this guide channel serving to guide this fluid in its rotation in relation to the axis of the wheel. The rings 25 and 26 are made of a light weight metal such as aluminum, or an alloy thereof, which has a greater temperature coefficient of expansion than iron or steel which is the material used for the casing elements 11 and 12.

15 In Fig. 1, the outer guide, or shroud, ring 25 is mounted in an annular channel, in the casing; said annular channel having a bottom surface 28 and having parallel side walls 29—30. Substantially no clearance is provided between the parallel side walls of the channel and the ends of the ring 25, but a substantial clearance is provided between the outer surface of the ring and the bottom surface 28 in the channel, for radial expansion. The clearance space in this channel exists during low temperatures, such as exist at starting, and does not interfere with the opera-

tion of the coupling, since there is substantially no leakage between the parallel channel sides and the sides of the diaphragm ring. When the coupling heats up, the larger expansion of the guide diaphragm relatively to the casing, eliminates this clearance space, but no radial pressure is exerted upon, and no strains are set up within, the casing.

Fig. 2 is a plan elevation of the coupling illustrated in Fig. 1 having the shell 12 removed to illustrate the means for mounting the guide vane diaphragm, centrally, within the casing. For this purpose, four equally spaced projections or lugs 32 are provided. These lugs project above the channel surface 28 and project into slots 33 in the ring. The slots in the diaphragm ring are made only slightly wider than the lugs in the channel so that there is a slide fit between the two, but no clearance space. A clearance space is left, however, between the end surface of the lug 32 and the bottom of the slot 33. With this arrangement and spacing of the lugs and slots, the diaphragm is held centrally within the hydraulic casing at all temperatures. Simultaneously, a radial expansion is provided in all directions.

In Figs. 3 and 4, a modified guide diaphragm is illustrated. This guide diaphragm comprises an outer, or shroud, ring 35, guide vanes 36, and an inner, or central, ring 37. The outer, or shroud, ring 35 is provided with three equally spaced slots 38, and the inner ring 37 is provided with three equally spaced slots 39 as shown in Fig. 4. The slots 38 and 39 are radial and are spaced intermediate each other. The diaphragm fits into the casing tightly at all temperatures. At low temperatures the slots 38 and 39 are at their full widths. During high operating temperatures, however, the segments of the rings expand sufficiently to close, substantially, these slots. In view of the fact that each segment expands by itself, the outer diameter of the ring remains constant, and substantially no radial stresses are applied to the casing.

In Fig. 5, a modified outer ring and a modified annular channel are used. An annular channel in the casing is provided with a cylindrical bottom surface 41 and with conical sides 42 and 43 which give this channel a cross-section which resembles a frustum of a cone. The end surfaces of the ring 44 are also conical and parallel to the sides of the channel. Furthermore, the width of the ring 44 and, therefore, the spacing of the end surfaces of the ring is such that the ring does not fill the channel and a clearance space is left between the circumference of the ring 44 and the bottom surface 41 of the channel at starting temperatures. During operation, the ring expands at a greater rate than the casing, and is, therefore, forced deeper into the wedge-shaped channel. The radial forces exerted by this expansion are relatively small in view of the fact that the pressure is actually exerted upon the conical sides and is to a great proportion in a horizontal direction. In view of the fact that the diaphragm is in contact with these conical sides, at all temperatures, it is centrally supported throughout the operating temperature range, and no special means are needed for centrally supporting the diaphragm.

Fig. 6 discloses a modification of the outer ring 44 of the guide vane diaphragm illustrated in Fig.

5. In this modification the ring is provided with slots 45 and 46 extending inwardly from the sides

of the ring. The slots 45 and 46 are similar to the slots 38 in the ring 35. They do not split the ring completely but extend inwardly from the sides of the ring up to the sides of the guide vanes and are spaced from each other in any desired manner. An equal spacing is preferable, and the number of slots used is dependent upon the resiliency and size of the diaphragm. In the illustrated coupling three equally spaced slots are used on each side of the ring. During operation, the ring expands and as it moves into the narrower part of the channel the ends of the ring contract, thereby still further reducing the radial pressure against the channel sides.

Fig. 7 illustrates a modification of Fig. 2. In this modification three equally spaced lugs 47 are provided in the periphery of the guide vane diaphragm ring 48. Three slots 49 are correspondingly provided in the bottom surface 50 of the channels in which ring 48 is mounted. In this modification, a clearance space is left between the end surface of the lug and the bottom of the supporting slot and a slide fit is provided between the sides of the lug and slot. In this manner, the diaphragm ring is supported at three equidistant points, and therefore, remains centrally within the casing at all temperatures. A clearance space is left at all points of the circumference so that a radial expansion is possible within the casing without the application of radial stresses against the casing.

What we claim as new and desire to secure by Letters Patent of the United States is:

1. In a hydraulic power transmitting device, the combination of a metal casing, a guide-vane diaphragm made of a metal having a higher coefficient of expansion than the metal of said casing, and means providing radial resiliency in said diaphragm to compensate for this difference in coefficients of expansion.

2. A diaphragm for a hydraulic coupling comprising a central ring, guide vanes attached to the periphery of said central ring, and a shroud ring engaging the outer ends of said vanes characterized in that said central ring is divided into segments and said shroud ring is divided into segments, the dividing points on said central ring and said shroud ring being intermediate each other.

3. In a hydraulic coupling the combination of a casing, a pump wheel and a turbo wheel therein and a guide diaphragm, said diaphragm comprising an inner ring divided into segments, guide vanes attached to said segments, and a shroud ring attached to the outer end of said guide vanes, said shroud ring being divided into segments at points circumferentially intermediate the points of division between said inner ring segments.

4. A diaphragm for a hydraulic coupling comprising a central ring divided into segments, said segments being spaced from each other by gaps which are substantially closed at normal operating temperatures, guide vanes attached to the periphery of said central ring, and a shroud ring attached to the outer end of said guide vanes, said shroud ring being divided into segments at points intermediate the dividing points on said central ring, said shroud ring segments being spaced from each other by gaps which are substantially closed at normal operating temperatures.
